UNITED STATES PATENT OFFICE.

DANIEL E. POWERS, OF NEW YORK, N. Y., ASSIGNOR TO THE PATENT PAPER CIGAR BOX COMPANY, OF SAME PLACE.

CIGAR-BOX.

SPECIFICATION forming part of Letters Patent No. 352,200, dated November 9, 1886.

Application filed September 7, 1886. Serial No. 212,924. (No model.)

To all whom it may concern:

Be it known that I, DANIEL E. POWERS, a citizen of the United States, residing at New York, in the county of New York and State 5 of New York, have invented certain new and useful Improvements in Cigar-Boxes; and I do hereby declare the following to be a full, clear, and exact description of the invention, such as will enable others skilled in the art to which 10 it appertains to make and use the same.

The object of this invention is to provide a cigar-box which can be produced economically as regards both material and workmanship, which shall have sufficient strength to withstand 15 the usual pressure incident to the packing of the cigars, and which will present an attractive appearance.

Figure I of the accompanying drawings is a perspective view of the blank designed to 20 constitute the bottom and ends of this improved cigar-box, in connection with a blank, partly broken away, designed to constitute one side thereof. Fig. II is a longitudinal section of this improved cigar-box on line *i* of Fig. III. Fig. III is a transverse section of this improved cigar-box on line *i i i* of Fig. II. Fig. IV is a perspective view of this improved cigar-box in a finished state.

Similar numerals of reference indicate corresponding parts in the different figures.

This improved cigar-box is preferably composed in part of pasteboard and in part of wood, and comprises a rectangular blank, 1, designed to constitute the bottom and ends of 35 the box, the former of a single and the latter of a double thickness, two similar rectangular blanks, 2 and 3, designed to constitute the front and rear sides of the box, respectively, and a rectangular blank, 4, designed to constitute 40 the top or cover thereof.

The blank 1 is composed of pasteboard and provided with two parallel transverse outer scores, 5, at a distance from its ends equal to the interior height of the latter, and with two 45 transverse inner scores, 6, at a distance from the ends of the blank equal to twice the height of the box. These scores 5 and 6 divide the blank into a bottom section, 7, two end sections, 8, constituting outer layers of ends of

the box, and two end sections, 9, constituting 50 the inner layers of the ends of the box.

The blanks 2 and 3 are of a width equal to the height of the box less the thickness of the cover and bottom thereof, and are of a length equal to the interior length of the box. The 55 blank 2, constituting the front side of the box, is preferably composed of wood, and the blank 3, constituting the rear side of the box, is also preferably composed of wood; but pasteboard or other suitable material may be used there- 60 for. The cover-blank 4 is of a width equal to the exterior width of the box, and of a length equal to the exterior length of the box less the thickness of the ends thereof.

In setting up this improved cigar-box, the 65 blank 1 is first folded on the lines of the outer scores, 5, forming a double thickness of the material between the scores 5 and 6 at opposite ends of the blank. The sections 9 are then folded into position at right angles to 70 the bottom section, 7, the material at the angle being upset in such manner that the edge of the bottom section is flush with the outer surface of the outer layers, 8. The side blanks, 2 and 3, are then placed in position at opposite sides of the blank 1, between the double ends thereof, and nails are passed through 75 said double ends into the ends of said side blanks, if the latter be composed of wood, securing them firmly in position. Nails may 80 also be passed through the bottom sections into the side sections. If the side blanks be composed of pasteboard, they are secured by strips of muslin 10, pasted or glued upon the edges of the bottom, sides, and ends. The 85 end sections, 8 and 9, which are folded in contact with each other, are pasted or cemented together. The cover is preferably hinged to one side of the box by means of a cloth hinge, in the ordinary manner, and shuts between 90 the ends of the box flush with the upper edges thereof. A nail or other fastening device may be used to secure the cover at the front side of the box. The joints and corners of the box are preferably covered on its exterior by strips 95 11, of ornamental paper, in the usual manner, and the interior of the box may be lined and labeled according to fancy.

In order to utilize waste stock, one or both of the end sections, 9, may not be cut integral with the blank 1; but, instead thereof, a separate rectangular piece may be inserted, cut 5 from scrap material, as shown in Fig. II.

The pasteboard blanks are preferably cut from straw-board, and preferably that which is covered on one side with paper stamped in imitation of cedar wood.

10 A box thus constructed is strong, stiff, durable, and symmetrical, and can be produced cheaply in a great variety of sizes without the use of expensive machinery for each different size.

15 I claim as my invention—

The combination, in a cigar-box, of a rectangular main blank comprising a rectangular bottom section, and two end sections at each end folded upon each other and constituting double layers at each end, said end sections being folded at right angles to the bottom section, and two blanks constituting the sides of the box, the folded layers of the double ends being cemented together, substantially as described.

DANIEL E. POWERS.
